United States Patent Office.

LUCIUS WHEATON, OF AUBURN, NEW YORK.

Letters Patent No. 71,254, dated November 19, 1867.

IMPROVED TRUNK-HINGE.

The Schedule referred to in these Letters Patent and making part of the same.

TO ALL WHOM IT MAY CONCERN:

Be it known that I, LUCIUS WHEATON, of Auburn, in the county of Cayuga, and State of New York, have invented certain new and useful Improvements in Trunk-Hinges; and I do hereby declare that the following is a full, clear, and exact description thereof, reference being had to the accompanying drawings, and to the letters of reference marked thereon, which form a part of this specification, in which—

Figure 1 is a rear elevation.

Figure 2, a side elevation, with the top portion of the hinge thrown back; and

Figure 3, a perspective.

The nature of my invention consists in so constructing a hinge that its sides will lap and bind the corners of a trunk, and thus protect the same, substantially as hereinafter described.

A B represent the two parts of the hinge, their sides forming right angles, as indicated in fig. 3; thus, when placed or secured to the trunk, additional strength will be given to the corners formed by the rear side and the ends, and also, in a great measure, protect the same from injury. *e* represents a vertical slot in the upper part of the hinge, as seen in fig. 1. The upper portion of the lower part B is extended on its end sides, as shown in fig. 2. This extension fits into slot *e*, and affords still further strength and protection to the trunk, while it adds increased strength to the hinge. *g* is a projection, on the upper part A, which acts as a stop to the lid of the trunk. *i i* are tack-holes.

What I claim, and desire to secure by Letters Patent, is—

The upper part A, provided with slot *e*, in combination with lower part B, when both are constructed and hinged, substantially in the manner specified.

In testimony that I claim the foregoing as my own, I affix my signature in presence of two witnesses.

LUCIUS WHEATON.
